UNITED STATES PATENT OFFICE

2,005,235

RADIATOR STRUCTURE

Arthur B. Modine, Racine, Wis., assignor to
Modine Manufacturing Company, Racine, Wis.,
a corporation of Wisconsin

Application July 22, 1931, Serial No. 552,362

1 Claim. (Cl. 257—130)

The invention relates to radiator cores and has among its principal objects the provision of means for increasing the rate of heat exchange between the indirect heat radiating surface such as the fins of the core and the air passing over said fins.

A further object of the invention is to provide a fin with a plurality of air passages extending in the direction of the air passing over the fins, this portion of the fins providing means whereby the rate of heat exchange is increased.

It is also an object of the invention to provide a structure having the above mentioned advantages with means for creating turbulence of air passing over said fin.

In addition it is an object of the invention to provide a radiator having a fin constructed with means for increasing the rate of heat exchange between said fin and the air passing over said fin and having another fin associated therewith, the latter having means for causing turbulence of air and directing said air toward the first mentioned fin.

The invention has these and other objects, all of which will be explained in detail and more readily understood when read in conjunction with the accompanying drawing which illustrates an embodiment of the invention, it being therefore obvious that other changes and modifications may be resorted to without departing from the spirit of the invention as defined in the appended claim forming a part hereof.

In the drawing,

Fig. 1 is a front view of a radiator core associated with other elements to provide a radiator;

Fig. 2 is a front elevation of a fragment of a structure embodying features of the present invention.

The invention contemplates utilizing a plurality of tubes 10 which are connected together by the fins 30 and 31 arranged transverse to the length of the tubes. In the structure illustrated the tubes 10 are connected with header tanks respectively designated 12 and 13. Each of the fins 30 and 31 are provided with a plurality of apertures for the reception of the tubes 10 and

the material of certain of the fins located between a pair of the tubes is crimped or corrugated to provide a plurality of air passages 16 arranged transversely of the length of the fin, which also extend in the direction of the air passing over said fins.

The arrangement shown in Fig. 2 contemplates the utilization of a fin 30 which is provided with corrugations, and the combination therewith of a fin 31 which is interposed between the fins 30 and is provided with means for creating turbulence of air, the means causing the air passing over the fin 31 to be circulated from one side of the fin 31 to the other into contact with the corrugated portions of the fins 30 located upon opposite sides of said fin 31. The means causing this turbulence is designated 32.

From the foregoing description of the invention, it is evident that a construction is provided whereby the heat dissipating capacity of a core 20 is increased. It is further manifest that the means employed does not impede or materially interfere with the passage of air through the core but on the contrary provides a plurality of channels arranged transversely of the fins which extend in the direction of travel of the air passing over said fins. It is further manifest that the structure may be provided with means whereby turbulence of air is created and caused to travel a tortuous path to thereby increase the heat 30 dissipating effect.

Having thus described the invention, what I claim as new and desire to cover by Letters Patent is:

A radiator core comprising a plurality of tubes 35 and transverse fins mounted upon said tubes, certain of said fins having transverse corrugations formed therein between the tubes, in combination with fins having flat non-corrugated surfaces on opposite sides thereof arranged intermediate said corrugated fins, said flat fins having apertures therein, and means at said apertures adapted to engage and direct a part of the air passing through the radiator through said apertures and toward an adjacent fin.

ARTHUR B. MODINE.
